UNITED STATES PATENT OFFICE

KEITH CLARK, OF RIDGEWOOD, NEW JERSEY

DESIGN FOR A PAD CALENDAR

Application filed May 16, 1929. Serial No. 31,257. Term of patent 14 years.

To all whom it may concern:

Be it known that I, KEITH CLARK, a citizen of the United States, and a resident of the city of Ridgewood, county of Bergen, and State of New Jersey, have invented a new, original, and ornamental Design for Pad Calendars, of which the following is a specification, reference being had to the ac-

companying drawing, forming part hereof.

Figure 1 is a plan view of a pad calendar showing my new design, and

Figure 2 is a side elevation thereof.

I claim:

The ornamental design for a pad calendar, as shown.

KEITH CLARK.
